UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,270,479.

Specification of Letters Patent. Patented June 25, 1918.

Original application filed March 22, 1909, Serial No. 485,046. Divided and this application filed August 14, 1917. Serial No. 186,106.

To all whom it may concern:

Be it known that I, WALTER WRIGHT, a citizen of the United States, residing in New York, in the county of New York and State of New York, have invented certain new and useful Improvements in Combined Type-Writing and Computing Machines, of which the following is a specification.

This invention relates to an improvement in combined typewriting and computing machines, and is a division of my application No. 485,046, filed March 22, 1909, which has become Patent No. 1,244,397, dated October 23, 1917.

15 The present case deals with a modified form in which a plurality of cross-totalizers is employed. A relative movement is provided between the totalizers and the master wheel. Preferably the wheels or actuators are 20 united to move in unison while the totalizers remain stationary, although the invention is not limited to this arrangement. The jumping elements, in this instance the master wheels, are connectible through a 25 train of mechanism to the typewriter carriage, so that they will vibrate back and forth several times for a single run of the carriage. The numbers typewritten in a horizontal line on the work-sheet carried 30 by the carriage are thus cross-totaled. Each totalizer is provided with its own 35 reverse gear mechanism, so that the totalizers may both add or subtract in unison, one may add and the other subtract, or one may be active while the other is silent. In this way a large number of different types of computation can be carried on, and for the different types of work each totalizer will give the result desired.

40 Other features and advantages will hereinafter appear.

In the accompanying drawings.

Figure 1 is a front view in elevation, with parts omitted to simplify the showing.

45 Fig. 2 is a detail side view in elevation, showing the gearing trains from the motor, and the escapement indexing mechanism to the master wheel and tens-carrying shafts.

Fig. 3 is a skeleton perspective view 50 showing the train of gearing from the typewriter carriage to the traveling mechanism, which controls the vibratory movements of the master wheels.

Fig. 4 is a vertical section through the friction clutch for connecting the motor to

the master wheels, which enables the motor to rotate idly when the master wheels are locked against rotation by the escapement indexing mechanism.

Fig. 5 is a detail vertical section, showing the pin-wheel, and the stop wheel for the same.

Fig. 6, is a horizontal section, showing the pin-setting mechanism.

Fig. 7 is a horizontal section of the mechanism shown in Fig. 6, showing the driving connection to the motor, which drives the same.

Numeral keys 1 depress key levers to operate type-actions (not shown), so as to print digits, corresponding to the keys actuated, on the work-sheet carried by a platen 2. The platen 2 is mounted to rotate on the usual typewriter carriage 3. This typewriter carriage 3 has the usual step-by-step advancing movement at the actuation of the keys 1, so as to space the digits as written and also to assist in giving a relative movement between parts of the computing mechanism.

The numeral keys 1, in addition to writing the digits, also operate the computing mechanism to add or subtract the digits as typewritten. For this purpose, each of the numeral keys as depressed, draws down on a link 4 to rock a bell crank 5, so as to pull on a link 6, which is connected to rock a bell crank 7, carrying on one arm thereof a plunger or jack 8. By this means when any one of the numeral keys from "1" to "9" is depressed, the associated plunger or jack 8 is thrust forward to set the opposite pin 9 of a ring of pins adjustably mounted in an escapement or pin-wheel 10. The pins 9 have two positions, one unset, projecting to the left of the pin-wheel 10 (Fig. 6), and the other set, projecting to the right of the pin-wheel 10. Normally, the pin last used in determining a computing action is set with one end projecting to the right of the pin-wheel 10 (Fig. 6), so as to engage a stop wheel 11, which holds the pin-wheel 10 against rotation.

The pin-wheel 10 is normally under a tendency to rotate, due to the driving action thereon from a motor 12. The motor 12 is connected to the pin-wheel 10 by a train of gearing 13, which includes a slip-clutch 14, illustrated in Figs. 4 and 7. When the pin-wheel 10 is locked against rotation by 110

the stop wheel 11, then the motor 12 rotates idly. When, however, the stop wheel 11 rotates aside to permit a rotation of the pin-wheel 10, then the friction clutch 14 forms a positive element of the driving train 13 from the motor 12 to the pin-wheel 10. The train of gearing 13 includes a shaft 15, to which the pin-wheel 10 is secured. This shaft 15 is driven by a series of gears 16 forming part of the train of gearing 13, and connects to one of the elements of the clutch 14.

The stop wheel 11 is normally held against movement, so that it prevents a rotation of the pin-wheel 10 by the motor 12, until one of the numeral keys is depressed. At each depression of one of the numeral keys from "1" to "9" to set one of the pins 9, mechanism is also operated to release the stop wheel 11 and thus release the pin-wheel 10. This includes heads 17, one of which is provided on each of the links 6 arranged when the unit numeral key is actuated to engage and operate a universal disk 18. This universal disk 18 is connected to operate a lever 19 against the tension of a spring 20. The lever 19 thrusts on a link 21, so as to rock a shaft 22 through the intermediary of an arm 23 secured to the link 21, and connected 30 to operate the shaft 22.

The specific manner of rocking the shaft 22 is more particularly described in the patent above referred to. It is sufficient to say, however, that at the depression of the numeral key, the shaft 22 is rocked so as to bring an open space in a disk 25 into register with one of the arms of a star wheel 26. Normally, the disk 25 is in engagement by one of the arms of the star wheel 26, and prevents a rotary movement of the star wheel and also of a shaft 27 on which the star wheel 26 is secured. The stop wheel 11 is also secured to the shaft 27, so that the rocking of the shaft 22 controls the rotation of the pin-wheel 10. During the down-stroke of the numeral key, however, the star wheel 26 and the stop wheel 11 are not permitted to rotate far enough to let the pin-wheel 10 escape. That is to say, the arm 50 of the star wheel 26, which escapes the first disk 25, comes into engagement with a second disk 28, also secured to the rock shaft 22 slightly beyond the disk 25.

At the return of the numeral key and at the completion of the escapement movement of the carriage in the manner more particularly explained in the patent, the shaft 22 is rocked backwardly so as to bring an opening in the disk 28 in register with the arm of the star wheel 26 in engagement with the disk 28. This permits the star wheel 26 and the stop wheel 11 to rotate one quarter of a revolution, allowing the previously set pin 9 to escape from the stop wheel 11. The pin-wheel 10 will then be

rotated by the motor 12, until the just set pin, the setting of which released the pin-wheel, comes into engagement with the next tooth of the stop wheel 11. By this time the next arm of the star wheel 26 will have 70 come around into engagement with the first disk 25, so that the pin-wheel 10 will be again locked against rotation. The previously set pin is restored to an unset position during the rotation of the pin-wheel 10 75 by a cam 30 located in the path of rotation of the set pins.

Thus, this pin-wheel escapement mechanism forms an indexing or valuating mechanism which controls rotations of the shaft 80 15 in amounts corresponding to the values of the numeral keys actuated. The indexed or valuated drives of the shaft 15 by the motor 12, under the control of the numeral keys, are transferred by a train of gearing 85 to master wheels 31 and 32 of totalizers 33 and 34. The train of gearing includes a beveled gear 35 on the shaft 15, which meshes with and drives a beveled gear 36 on a horizontal shaft 37. The shaft 37 90 drives, through the intermediary of meshing gears 38 and 39, a vertical shaft 40. The vertical shaft 40 drives master wheel shafts 41 and 42 on which the master wheels 31 and 32 are splined. The connection of the 95 shaft 40 to the master wheel shafts 41 and 42 is such that the master wheel shafts can be rotated selectively in either direction and one of the master wheel shafts can be rotated while the other is silenced. This 100 enables the driving of either of the totalizers 33, 34 for addition, while the other is subtracting, and also enables either of the totalizers to be active while the other is passive.

For this purpose, a reverse gearing connection is provided between the shaft 40 and each of the master wheel shafts 41 and 42. This reverse gearing connection includes two pairs of oppositely facing 110 beveled gears, indicated by the numbers 43, 44 and 45, 46. These gears are loosely mounted on the shaft 40 and the pair 43, 44 mesh with and drive a beveled gear 47 secured to the master wheel shaft 41, while 115 the pair of beveled gears 45, 46 mesh with and drive a beveled gear 48 secured to the master wheel shaft 42. Intermediate the pair of beveled gears 43, 44, and splined on the shaft 40, there is provided a beveled 120 clutch 49, which may be shifted alternatively from an intermediate non-connecting position upwardly to clutching engagement with the gear 43, or downwardly to clutching engagement with the gear 44. Thus, 125 the gears 43, 44 may be secured in driven relation with the shaft 40. Similarly, a clutch 50 is located between the pair of beveled gears 45, 46, and slidably secured to the shaft 40, so as to be shiftable from 130

an intermediate neutral position to a position securing the gear 45 or the gear 46 in driven relation with the shaft 40.

Each of the totalizers 33, 34 includes computing wheels 51, some of which have numbers on their periphery to form dial wheels, exhibiting the sums that run up by the master wheels 31, 32 through a sight-opening 51^a in the casings of the totalizers 10, 33, 34. The particular driving train between the master wheels and the dial wheels is more particularly described in my patent. When the dial wheel completes a revolution one is carried from such dial wheel to 15 the next higher dial wheel. This is done by a tens-carrying mechanism also more fully described in the patent.

The tens-carrying mechanism is assisted in its action by the motor 12, which is connected by gearing 52 to drive a shaft 53. The shaft 53 drives a vertical shaft 54 by means of meshing gears 55, 56. The vertical shaft 54 is connected to rotate the tens-carrying assisting shafts in a manner similar to the rotation of the master wheel shafts 41, 42. That is to say, the assisting tens-carrying shafts may be rotated in unison in the same direction, one rotated in either direction while the other is rotated 25 in the opposite direction, and one rotated in either direction while the other is passive.

This arrangement is such that the assisting shafts will correspond in their rotation and direction of rotation with the rotation 30 and direction of rotation of the master wheel shaft for the same totalizer. The connection includes a reversible gearing for each totalizer. For the upper totalizer 33, this reversible gearing includes a pair of oppositely facing gears 56^a, 57 loose on the shaft 54, which mesh with and drive a beveled gear 58, secured to the tens-carrying assisting shaft for the upper totalizer, 33. The reversible gearing for the lower totalizer 34 includes oppositely-facing beveled 35 gears 59 and 60, loose on the shaft 54 and meshing with to drive a beveled gear 61 secured to the assisting shaft of the lower totalizer 34. A double clutch 62 is splined 40 on the shaft 54 and interposed between the beveled gears 56^a and 57, so as to be shiftable into mesh with either of them to connect either of them in driven relation to the shaft 54. Similarly a double clutch 63 is splined on the shaft 54 between the beveled gears 59 and 60, and is shiftable to connect either the beveled gear 59 or the beveled gear 60 in driven relation to the shaft 54. So that the change in the drive and character of drive for the master wheel shaft and the tens-carrying mechanism may be accomplished concomitantly, the clutches 49 and 62 are operated by a lever 64 common to both of them, and having pins 65 and 66 engaging in grooves provided in clutches

49 and 62. Similarly, the clutches 50 and 63 are moved in unison by a lever 67, which has pins 68 and 69 engaged in grooves provided in the clutches 50 and 63. While the master wheel and tens-carrying clutches are moved in opposite directions, the trains of gearing from the motor and the indexing mechanism is such that their movements in unison correspond. That is to say, the rotations of the master wheel and the tens-carrying assisting mechanism are such that both rotate to add or both rotate to subtract.

The principal feature of the present case includes the means for traversing the master wheels 31, 32 in unison with each other, so that they will drive step by step corresponding computing wheels in two totalizers 33, 34. This drive may be varied, as explained above, according to the type of work it is desired to perform. In order that the master wheels 31, 32 may travel in unison, they are rotatably connected to sleeves 70, 71 (Fig. 1), which are loosely mounted on the master wheel shafts 41, 42. The connections of the sleeves 70, 71 to the master wheels 31, 32 are such that the master wheels can slide along the shafts 41 and 42 and be rotated thereby, and yet rotate relatively to the sleeves 70, 71, which traverse the master wheels. The sleeves 70, 71 are connected by a cross bar 73, so as to form a duplex master wheel carriage 74, insuring that the master wheels 30, 31 always travel in unison.

The master wheel carriage 74 is controlled in its step-by-step movement from the typewriter carriage 3. For this purpose, there is provided on the rear of the typewriter carriage 3 a rack bar 75 (Fig. 3), which meshes with and drives a gear 76 secured to a vertical shaft 77. The shaft 77 drives through a pair of intermediary meshing gears 78, 79, a horizontal shaft 80. The shaft 80 extends forward in front of the machine, where it is provided with a gear 81, meshing with and driving a rack bar 82. The rack bar 82 is slidably mounted at the front of the machine by means of ways 83, so as to travel back and forth in unison with the typewriter carriage 3.

In addition to being provided with a rack, the bar 82 is provided with a series of openings 84, arranged at suitable intervals so as to provide means of attachment for pick-up or column stops 85. A plurality of these stops 85 are provided according to the number of major columns or computing zones desired, and they are selectively adjustable along the bar 82 according to the relative positioning of the zones desired. Each of the stops 85 is provided with a depending lug 86, which is arranged to engage in a notch 87, provided in a shifter 88. The stops 85 are arranged to pick up the shifters 88, one by one, as the typewriter carriage 3

travels from right to left. The movement of the stops 85 with the bar 82, however, is from left to right. The train of gearing from the rack 75 to the rack bar 82 is designed for this purpose. The notch 87 is provided with a tall wall 89 on its right-hand side (Fig. 1), so that as each stop 85 engages the shifter 88 for a driving movement, the engagement will be positive. On the opposite side the notch 87 is provided with a short wall 90, which will permit each stop to readily disengage from the notch and yet will catch each stop sufficiently to prevent accidental disengagement, due to a rebound. The shifter 88 is connected to the master wheel carriage 74, so as to traverse the same, and is yieldingly held in an active position by a spring 91.

The stops 85, when in individual engagement with the shifter 88, traverse the shifter, the master wheel carriage 74 and the master wheels 31 and 32, step by step to the right with a step-by-step advancing movement of the typewriter carriage 3 to the left. In this way, the master wheels 31, 32 are brought into individual driving register with the series of computing wheels of the two totalizers 33, 34. Each stop 85 corresponds to a single computing zone and to a single run of the master wheels 31, 32. When the master wheels 31, 32 reach the limit of their travel to the right, or, in other words, come into register with the units computing wheels in the totalizers 33, 34, then the master wheel carriage 74 is disconnected from the typewriter carriage 3, so as to permit the master wheels to be repositioned in register with the computing wheels of highest denomination for a new run and a new computing zone. This is accomplished by a disconnector or stop 92 located in the path of an incline or slope 93, provided on the shifter 88. When this slope 93 comes into engagement with the disconnector or stop 92, the shifter 88 is depressed against the tension of the spring 91, so as to withdraw the shifter from engagement, which ever stop 85 happens to be in register.

When the shifter 88 and the master wheel carriage 74 are thus disconnected from the typewriter carriage 3, they are free to return to their starting position. The return movement is accomplished by a spring drum 94 connected to the master wheel carriage 74 by a flexible connection 95. During the step-by-step advancing movement of the master wheel carriage 74 to the right, this flexible connection 95 was unwound, so as to wind up the spring of the drum 94; thus, when the traction pull from the typewriter carriage is withdrawn, the spring drum 94 is free to wind up the flexible connection 95, and thus return the master wheels 31, 32, the master wheel carriage 74 and the shifter 88 to the left, their initial starting position.

By the adjustment of the pick-up stops 85 and the disconnector 92, the period of connection of the master wheel carriage 74 with its shifter 88 can be varied. The disconnector 92 is made adjustable for this purpose, and includes an arm 96 having a roller 97 to engage the slope or incline 93. The arm 96 is pivotally supported by means of a set screw 98, which can be loosened sufficiently to permit the arm 96 to swing up or down, so as to vary the disconnecting position of the roller 97, and is then tightened to hold the arm 96 and the roller 97 in the selected adjusted position. In this way, the disconnector 92 may be made to release the shifter 88 sooner or later from the pick-up stops 85.

In order that the typewriter carriage 3 may not attempt to carry the master wheel carriage 74 beyond its completely returned position when the typewriter carriage is returned, there is provided a second disconnector or stop 99, which is located to engage an incline or slope 100, provided on the shifter 88 on the opposite side of the notch 87 to the slope or incline 93. The relation of the disconnector 99 and the slope 100 is such that the spring drum 94 is not sufficiently strong to depress the shifter 88 to such a position that the high wall 89 will not reach the depending lug 86 on the pick-up stops 85, when the typewriter carriage 3 travels in an advancing direction.

If it is desired to disconnect the traveling master wheel carriage 74 and thus the master wheel from the typewriter carriage 3, so that there will be no step-by-step movement of the master wheels, a manual disconnector 101 is provided, which has a pin 102 overlying the shank of the shifter 88 and arranged to depress the same to such a position as to withdraw the tall wall 89 clear of the path of movement of the lugs 86 on the pick-up stops 85.

The utility of this form of the invention will be readily understood when taken in connection with the above description. The pick-up stops 85 and the disconnector 92 are adjusted according to the character of work desired. This includes the number of digit columns in the computing zones and the magnitude of the computing zones. The levers 64 and 65 may be shifted back and forth as the work progresses, so as to have the totalizers add or subtract or be neutral as the need arises. This arrangement is very advantageous for billing purposes. For instance, the items of the bill may be set down in a column and computed by one of the mechanisms, say the upper, the lower one being at that time inoperative. When the lower mechanism is set for "addition", and the upper mechanism is set for "subtraction", and the total is written down in another column, to the right or left of the first column, then the upper mechanism is

thereby reset to zero, while the total is retained in the lower mechanism. This operation may be repeated a number of times and the grand total obtained by the lower mechanism. Then, after so obtaining the grand total, the lower mechanism may be set for "subtraction" and the grand total written down in a third column, thus resetting the lower mechanism to zero. Or, instead of 10 pursuing the above method, a discount may be taken, or any amount deducted from any one or more of the totals, the lower mechanism being at that time and for that purpose set for "subtraction", and by setting 15 the lower mechanism to the inoperative position, the balance may be placed in the same or in another column and at the same time retained in the lower mechanism.

It will readily be seen that either of said 20 mechanisms can be operated, either for addition or for subtraction, the other being inoperative, or the two mechanisms can both be used for addition or for subtraction, or either one for addition and the other for 25 subtraction.

It will also be seen that by means of the clutch-operating levers 64 and 67, either cross-computing mechanism may have its 30 wheels returned to zero at will. If, for instance, a plurality of columns have been cross-computed in both the upper and lower totalizers, then the upper totalizer, for example, may have its lever 64 set to subtraction and the number indicated thereon struck 35 on the keys. This will result in turning the wheels of the upper totalizer to zero and at the same time transferring the amount standing thereon to the lower totalizer. The lower totalizer would, of course, in such a 40 case indicate twice the amount previously standing thereon, but this is not an objection in many kinds of work. Instead of proceeding in the manner set forth, the lower totalizer may be silenced while different columns 45 are being accumulated on the upper totalizer. The upper totalizer may then be reversed while the number standing thereon is struck on the keys. This will result in leaving the upper totalizer at zero. Of 50 course, other well-known means may be provided for returning the wheels of either totalizer to zero, other than those specifically shown.

When it is desired to increase the number 55 of such columns and the successive operations, three or more such horizontal mechanisms can be used in the same manner.

Variations may be resorted to within the 60 scope of the invention, and portions of the improvements may be used without others.

Having thus described my invention, I claim:

1. In a computing attachment for typewriters, the combination with a typewriter 65 carriage, of a device arranged to move with

the typewriter carriage, a plurality of computing mechanisms, individual actuators therefor, and means whereby, through the continued movement of said device with the typewriter carriage, repeated intermittent 70 movements may be produced of each actuator relative to its corresponding computing mechanism, substantially as described.

2. In a computing attachment for typewriters, the combination with a typewriter 75 carriage, of a device arranged to move with the typewriter carriage, a plurality of computing mechanisms, individual actuators therefor, means whereby either actuator may be rotated in either direction, independently of the other, and means whereby, through the continued movement of said device with the typewriter carriage, repeated intermittent movements may be produced of each actuator relative to its corresponding computing mechanism, substantially as described. 80

3. In a computing attachment for typewriters, the combination with a typewriter carriage, of a device arranged to move with the typewriter carriage, a plurality of computing mechanisms, individual actuators therefor, and means whereby, through the continued movement of said device with the typewriter carriage, repeated intermittent 90 movements may be produced of each actuator relative to its corresponding computing mechanism, means for automatically returning each actuator at the end of its movement, and means for variably limiting 95 the extent of return of the actuators at each such movement, substantially as described.

4. In a computing attachment for typewriters, the combination with a typewriter carriage, of a device arranged to move with the typewriter carriage, a plurality of computing mechanisms, individual actuators therefor, means whereby, through the continued movement of said device with the typewriter carriage, repeated intermittent 105 movements may be produced of each actuator relative to its corresponding computing mechanism, and means whereby after each such movement said actuators may be returned, through any desired portion of 110 the full possible return, substantially as described.

5. In a combined typewriting and computing machine, the combination with a traveling carriage, of a cross-adding device 120 comprising two limited totalizers traversable by said carriage, and a silencer for making said carriage ineffective on said totalizers.

6. The combination with a step-by-step-feeding carriage movable through a succession of computing zones, of a plurality of cross-computing mechanisms, each including a traveling element, automatic mechanism effective intermittently for connecting said traveling elements simultane- 125 130

ously to said carriage to be advanced thereby, and releasing them to return repeatedly independently thereof during a single run of said carriage, and shiftable means for causing one of said cross-computing mechanisms to perform either addition or subtraction.

7. The combination with a step-by-step-feeding carriage movable through a succession of computing zones, of a plurality of cross-computing mechanisms, each including a traveling element, and automatic mechanism effective intermittently for connecting said traveling elements simultaneously to said carriage to be advanced thereby, and releasing them to return independently thereof during a single run of said carriage, with provisions whereby at least one of said cross-computing mechanisms may be brought to zero independently of the other.

8. The combination with a letter-feeding carriage, of a plurality of cross-computing mechanisms, each including a traveling element, and automatic mechanism effective intermittently for connecting said traveling elements simultaneously to said carriage to be advanced thereby, and releasing them to return independently thereof during a single run of said carriage, with provisions whereby any one of said cross-computing mechanisms may be brought to zero independently of any other.

9. The combination with a letter-feeding carriage, of a plurality of cross-computing mechanisms, each including a traveling element, and automatic mechanism effective intermittently for connecting said traveling elements simultaneously to said carriage to be advanced thereby, and releasing them to return independently thereof during a single run of said carriage, with provisions whereby at least one of said cross-computing mechanisms may be silenced at will while others remain active.

10. The combination with a letter-feeding carriage, of a plurality of cross-computing mechanisms, each including a traveling element, and automatic mechanism effective intermittently for connecting said traveling elements simultaneously to said carriage to be advanced thereby, and releasing them to return independently thereof during a single run of said carriage, with provisions whereby any one of said cross-computing mechanisms may be silenced while others remain active.

11. The combination with a letter-feeding carriage, of a plurality of cross-computing mechanisms, each including a traveling element, automatic mechanism effective intermittently for connecting said traveling elements to said carriage to be advanced thereby, and releasing them to return independently thereof, and shiftable means for caus-

ing said cross-computing mechanisms to perform either addition or subtraction.

12. The combination with a letter-feeding carriage, of a plurality of cross-computing mechanisms, each including a traveling element, automatic mechanism effective intermittently for connecting said traveling elements to said carriage to be advanced thereby, and releasing them to return independently thereof, and shiftable means for causing either of said cross computing mechanisms to perform either addition or subtraction regardless of the nature of the computation performed by the other.

13. The combination with a letter-feeding carriage, of a plurality of cross-computing mechanisms, each including a traveling element, automatic mechanism effective intermittently for connecting said traveling elements to said carriage to be advanced thereby, and releasing them to return independently thereof, and shiftable means for setting either one of said cross-computing mechanisms to either addition, subtraction or neutral, independently of the other.

14. The combination with a letter-feeding carriage, of a plurality of cross-computing mechanisms, each including a traveling element, automatic mechanism effective intermittently for connecting said traveling elements to said carriage to be advanced thereby, and releasing them to return independently thereof and shiftable means to control the activity of said computing mechanisms and the character of the computation performed thereon.

15. The combination with a letter-feeding carriage, of a plurality of cross-computing mechanisms, each including a traveling element, automatic mechanism effective intermittently for connecting said traveling elements to said carriage to be advanced thereby, and releasing them to return independently thereof, and shiftable means to control the activity of one computing mechanism and the character of the computation performed thereon, independently of the other computing mechanism.

16. In a combined typewriting and computing machine, the combination with numeral keys and a letter-feeding carriage controlled thereby, of a plurality of cross-computing mechanisms, each computing mechanism comprising a set of computing wheels, denomination-selecting means controlled by said carriage for each of said cross-computing mechanisms whereby the latter are brought into use by said carriage repeatedly during a single run of the carriage, and means for controlling the activity and direction of movement of one computing mechanism independently of the other.

17. In a combined typewriting and computing machine, the combination with nu-

- meral keys and a letter-feeding carriage, controlled thereby, of a plurality of cross-computing mechanisms, each computing mechanism comprising a set of computing wheels, denomination-selecting means controlled by said carriage for each of said cross-computing mechanisms whereby the latter are brought into use by said carriage repeatedly during a single run of the carriage, and manually operable means for controlling the direction of movement of each cross-computing mechanism in any zone.
18. In a computing machine, the combination with a key-controlled drive-shaft, of a series of computing heads, a master-wheel for each of said computing heads, a shaft to which each of said master-wheels is splined, means to connect each of said master-wheel shafts to said drive-shaft, and means to move the master-wheels simultaneously along their shafts.
19. In a computing machine, the combination of a series of computing heads, a master-wheel for each of said computing heads, shafts to which said master-wheels are splined, one of said shafts for each master-wheel, a series of keys, means controlled by said keys for rotating said master-wheel shafts simultaneously, and means to move the master-wheels simultaneously along their shafts.
20. In a computing machine, the combination of a series of computing heads, a master-wheel for each of said computing heads, shafts to which said master-wheels are splined, one of said shafts for each master-wheel, a series of keys, means controlled by said keys for rotating said master-wheel shafts simultaneously in either direction, and means to move the master-wheels simultaneously along their shafts.
21. In combination, a series of computing heads mounted in single tier one below another, a series of master-wheels, the typewriter carriage, and the second carriage connected to the typewriter carriage and moving said master-wheels, and means being provided to cause the master-wheel carriage to move in the opposite direction from the typewriter carriage.
22. In combination, a series of computing heads mounted in single tier one below another, a series of master-wheels, the typewriter carriage, and the second carriage connected to the typewriter carriage and moving said master-wheels, and means being provided to cause the master-wheel carriage to move in the opposite direction from the typewriter carriage.
23. The combination with a computing head having a master wheel, of a device connected to said master wheel, a slide connected to said device, a hook or catch upon said slide, a typewriter carriage, a carriage adapted to move in the opposite direction from said typewriter carriage, a lug upon said second carriage engageable by said catch, means to release said catch, and means to return said slide and said master wheel upon said catch being released.
24. The combination of a typewriter carriage, a set of computing heads, a set of master-wheels, one for each computing head, means for connecting said master-wheels *en bloc* to the typewriter carriage to move step by step in the opposite direction from the latter, and means for automatically disconnecting said master-wheels *en bloc* from said carriage and returning the master-wheels, and re-connecting them to said carriage.
25. The combination with a typewriter carriage, of a second carriage, means to connect said carriages for movement in opposite directions, a set of master wheels connected to said second carriage to move therewith, a set of computing heads to coöperate with said master wheels, a slide, and a device between said slide and said second carriage for connecting said slide thereto.
26. The combination with a typewriter carriage, of a second carriage connected thereto for movement in the opposite direction, a set of master wheels connected to said second carriage to move therewith, a set of computing heads to coöperate with said master wheels, a slide, and means for connecting said slide to said second carriage and automatically disconnecting it therefrom and returning said slide and reconnecting it to the second carriage.
27. The combination with a plurality of computing heads, of a master-wheel individual to each of said computing heads, a master-wheel shaft for each of said master-wheels, a common drive-shaft for all of said master-wheel shafts, a series of numeral keys for controlling the extent of rotation of said common drive-shaft in either direction, a carriage traveling to control the relative position of said computing heads and said master-wheels, means for intermittently connecting said master-wheels to move with said carriage, and means for silencing one of said master wheel shafts at will.
28. The combination with a series of computing devices, each including two primary elements, to wit, a computing head and a master-wheel, of a master-wheel shaft for each of said master-wheels, a drive-shaft common to all of said master-wheel shafts, numeral keys for controlling the extent of rotation of said common drive-shaft, a traveling carriage, means for intermittently connecting one of the primary elements of all of said computing devices so as to effect a concomitant relative movement between all of the computing heads and the master-wheels, and means for silencing any master wheel shaft at will.
29. The combination with a plurality of computing devices, each comprising two primary elements, to wit, a computing head

and a master-wheel, of a master-wheel shaft for each of said master-wheels, a drive-shaft common to all of said master-wheel shafts, a series of numeral keys for controlling the extent of rotation of said common drive-shaft, means individual to each of said master-wheel shafts to determine the direction of drive of said master-wheel shafts individually by said common drive-shaft, where-
10 by some of said master-wheel shafts can rotate in one direction and others in the opposite direction, a traveling carriage, and means for intermittently joining one of said primary elements of all of said computing devices to move with said carriage so as to effect a concomitant relative movement between all of said computing heads and their master-wheels.

30. The combination with a typewriting mechanism including a traveling carriage, of a series of computing devices, each including two primary elements, to wit, a computing head and a master-wheel, mechanism for simultaneously connecting with and disconnecting from said carriage all of one type of said elements of said computing devices, and means for individually controlling the activity of said computing devices independently of their connection with
30 said carriage.

31. In a computing machine, the combination with printing mechanism and a traveling carriage for determining different columns in which numbers may be printed, of computing mechanisms for accumulating the numbers printed, and means for controlling said computing mechanisms to separately accumulate debit and credit items printed in columns located at variably selected places, during a single run of said carriage.

32. In a computing machine, the combination with printing mechanism and a traveling carriage for determining different columns in which numbers may be printed, of a computing head which may accumulate credit items, a computing head which may accumulate debit items, means for varying the positions of the printed columns, and
50 means for controlling said heads to accumulate items of the different classes in the respective computing heads, regardless of

the location of the columns, and during a single run of said carriage.

33. In a computing machine, the combination with a typewriter carriage, of a plurality of computing mechanisms arranged in tandem, individual actuators therefor, means whereby, through the continued movement of the typewriter carriage in one direction, repeated intermittent movements may be produced between each actuator and its corresponding computing mechanism, and means for silencing or reversing any actuator at will. 60
65

34. In a computing machine, the combination with a typewriter carriage, of a plurality of computing mechanisms, individual actuators therefor, means whereby, through the continued movement of the typewriter carriage in one direction, repeated intermittent movements may be produced between each actuator and its corresponding computing mechanism, and means for silencing one of said computing mechanisms at will. 70
75

35. In a computing machine, the combination with a typewriter carriage, of a plurality of computing mechanisms, individual actuators therefor, means whereby, through the continued movement of the typewriter carriage in one direction, repeated intermittent movements may be produced by each actuator relatively to its corresponding computing mechanism, and means for silencing either of said computing mechanisms at will. 80
85

36. In a computing machine, the combination of a frame, a plurality of computing mechanisms fixed relatively to the frame, and each having a series of computing wheels, individual actuator shafts and actuators thereon for said wheels, each actuator shaft exclusively rotating the computing wheels of the corresponding mechanism, means whereby the actuators of the respective shafts can be caused to repeatedly engage the computing wheels of the two mechanisms respectively in a plurality of adding zones, and means for controlling the activity and direction of movement of at least one of said actuators. 90
